DAVID J. HUNTER, OF EXETER, NEW HAMPSHIRE.

Letters Patent No. 96,920, dated November 16, 1869.

IMPROVEMENT IN BRICK-MACHINES.

The Schedule referred to in these Letters Patent and making part of the same.

To all to whom these presents shall come:

Be it known that I, DAVID J. HUNTER, of Exeter in the county of Rockingham, and State of New Hampshire, have originated an invention of a novel and useful Brick-Machine; and do hereby declare the following to be a full, clear, and exact description thereof, due reference being had to the accompanying drawings, making part of this specification, and in which—

Figure 1 is a plan,

Figure 2, a sectional side elevation,

Figure 3, an end elevation, and

Figures 4 and 5 are vertical and transverse sections of a machine embodying my invention, the latter section being taken through the brick-pressing moulds, to be hereinafter explained.

The invention embraced in the description herein to follow, and which comprises the subject-matter of this patent, is a machine for moulding and pressing bricks from "raw" clay, the principle sought in making the invention being to reduce the complication of parts and uncertainty of action heretofore existing in machinery of like character, the machine devised by myself, as will be seen, being very simple and economical in construction, and positive and regular, as well as certain in operation.

My present invention consists, first, in the employment of a large upright cylindrical tub or chest, mounted upon or within a strong frame of proper construction, the interior of the tub being provided with a revolving cylinder or agitator and mixer, which carries, at its lower part, a gate for alternately opening and closing two orifices made through the bottom of the tub at opposite points in its area, such gate serving to guide and direct the clay into sliding moulds disposed below these orifices, as hereinafter explained, a pair of plungers, operated by a suitable mechanism, being combined with each mould, to compress the clay within it, and a reciprocating block or ejector being situated above each mould, to advance the brick, as it emerges therefrom by the action of the ascending plunger, the whole being as hereinafter fully referred to and explained; various accessories to the above general features of the machine being, in their place, duly described.

In the drawings, to which allusion has before been made as accompanying this specification, and which illustrate my invention, the clay-receiving tub or chest is represented at A as an upright hollow cylinder, the bottom of the tub being an elevated platform, B, making part of a suitable frame or structure, C, for supporting the operating-parts of the machine, this structure or frame being composed of side posts, D D, and a cross-board or staging, E, the latter, which serves to steady the tub, being disposed at about two-thirds

the height of said tub, and forming a walk for the convenience of the operatives employed about the machine.

Within the tub A, I dispose a perpendicular revolving drum or mixer, F, preferably of the form of a conic frustum, the diameter of the base of this drum being about three-fourths that of the interior of the tub.

The drum F is supported upon an upright shaft, G, extending through the bottom of the tub, and stepped within a suitable block, H, erected upon or within the substructure of the machine.

The drum F is guided at top by a journal, a, extending from its centre and through a cross-bar, b, spanning the top of the tub.

The bottom of the drum F is closely contiguous to that of the tub, and has affixed to its edge a segmental flange or wing, c, which extends therefrom to the wall of the tub, and revolves with the drum directly over the bottom of the tub, the office of this flange being to direct portions of the clay alternately into two orifices, d d', made through the bottom of the tub at diametrically opposite points, the length of these orifices being equal to the width of the annular space intervening between the bottom of the drum F, and of the walls of the tub.

The advance portion, e, of the flange or wing, c, is inclined upward, in order to insure the passage of clay under it, the length of this segmental flange being less than a semicircle, for the reason that while one orifice is closed by it, the other should be open.

The moulds or matrices for producing the perfectly-formed brick, are shown at I I', as situated immediately below the platform or bottom B of the tub, and opening through it, and upon opposite sides of the centre of said tub, it being here observed that this machine is a double-acting one, that is to say, its working parts are duplicated upon each side of its centre.

The moulds I I' are in alignment with, and form continuations of the orifices d d', before mentioned, the clay, which is pressed through these orifices by the rotary movement of the drum and its wing, passing into the inner portion of these moulds.

J J' are twin horizontal plungers, playing easily within the inner portion of the moulds I I', such plungers being fixed to or making part of a bar, K, straddling the shaft of the drum F, the necessary reciprocating movements of the plungers being effected by an eccentric, L, mounted upon said shaft F, and disposed between and abutting against the inner ends of said plungers.

A revolution of the shaft and eccentric produces alternate reciprocations of the plungers into and out of the moulds, each plunger, at the extent of its out-

ird movement, filling the mould, less the length of e brick to be compressed within it.

While the action of these plungers determines the ngth of the brick, and the mould its smaller bulk, e degree of density of such brick is produced by two other upright plungers, $M M'$, disposed below the moulds, and travelling in suitable guides or bearings, j , the upper extremities of these plungers playing thin the moulds, as represented, and forming the ttom of the compression-chamber of the same, the dth of these plungers being equal to the length of e brick when compressed.

The vertical reciprocations of the plungers $M M'$ are effected by two wiper-cams, $N N'$, revolving with-slots, $O O'$, formed in each, these cams being mounted upon a horizontal transverse driving-shaft, extending across the machine-frame, and supported by bearings, $g g$, made in its side posts, $D D$, an anti-friction roller, h , being placed over, and bearing upon the cam, such roller being pivoted within the plunger, and supporting its weight; the object of introducing such roller at this point being to reduce the friction which would otherwise exist between the plunger and m.

I have shown the disposition of the moulds, and their compression-chambers are composed of open ots, I must provide a cover or top to such mould, being seen that the plungers $M M'$ serve as movable bottoms to the same, it being necessary that the over should also be movable, in order to allow of the expulsion of the brick from the mould, after compression thereon.

To provide this movable cover, I dispose, upon the p of the platform B , and over each orifice or open mouth of the compression-chambers of the moulds, a sliding gate, $k k'$, the proper intermittent movements of these gates over and away from the mould-openings being effected through the agency of a vibrating lever, or $l l'$, pivoted to the rear part of each, the lower end of each lever being mounted upon a rocker-shaft, $m m'$, supported in bearings, $n n$ or $n' n'$, erected upon the foundation or flooring of the machine, such rocker-shafts in turn being actuated by a wiper-cam, V or V' , fixed to the driving-shaft of the machine, and upon opposite sides of the drum-shaft G , each wiper being enclosed within a forked arm, p or p' , fixed to the inner end of each rocker-shaft, the arrangement of parts being such that a revolution of the wiper shall impart to the rocker-shaft a partial revolution through a small arc of a circle, the extent of this movement being sufficient to force the gate or cover in one direction over, and to close the mouth of the mould, and in the opposite direction sufficiently to entirely open such mouth.

The outer extremities of the gates $k k'$ should be supported in guides, q or q' ; while, to their upper surface, I have secured an inclined bed or bearing-surface, $r r'$, to the anti-friction roller, this inclined bed being applied in an adjustable manner, in order to vary the degree of pressure of the gate upon the platform B about the mouth of the moulds, this depression of the gate being effected by rollers, $s s'$, placed over them, and mounted upon shafts, $t t'$, extending through the machine-frame, as represented, the inclined beds $r r'$ serving as bearing-surfaces between the gate and roller, and, as before remarked, enabling the pressure of the gate about the mouth of the mould to be varied, in order to prevent escape of clay therefrom under all conditions.

The portion 3, of the cam N' , in practice, should be a segment of a circle, of somewhat larger radius than one struck from the axis of the cam, in order to relieve the brick from the pressure of the plunger M' , and allow the gate k to slide easily over it in the act of uncovering the mouth of the mould.

Rotary motion is imparted to the drum F by a bevelled gear, R , fixed to the lower part of its shaft,

this gear meshing into, and receiving motion from a second bevelled gear, S , mounted upon the driving-shaft P .

The form of the cams $O O'$ is exhibited plainly in fig. 5 of the accompanying drawings, as divided substantially into five working parts, numbered respectively from 1 to 5.

The portion 1 composes the smallest diameter of the cam, and is concentric with its axis, this portion of the cam serving to support the plunger M' when at its lowest position, the upper surface of the plunger at this time forming the bottom of the compression-chamber of the mould, and being in the same horizontal plane with the bottom of the horizontal plungers $J J'$, the wing c , at this time, being in the act of covering the orifice d through which its flaring portion has forced the clay.

The next portion of the cam, in order of rotation, or that marked 2, departs at a tangent from the axis of the cam, to such an extent as to elevate the plunger M within the compression-chamber of the mould, until its upper surface is level with that of the horizontal plunger J .

The portion of the cam marked 3 now begins, such part being a continuation of the greatest diameter of the preceding one, and being concentric with the axis of the cam, in order to give time for the opposite plunger J to begin its movements, this concentric portion 3, of the cam, occupying about one-sixth its circumference.

The portion 4 of the cam is a continuation of the portion 3, and departs from the axis of the cam at a considerable tangent; the office of this portion of the cam being to elevate the plungers $M M'$ to a level with the top of the platform B , and into the path of movement of the advancing gates $k k'$, by which the brick is pushed off the platform and upon an endless revolving belt, suitably placed to receive it. The latter part of the portion 4 of the cam is concentric with its axis, in order to aid in completing the circuit of the periphery of such cam, and to allow time for the advance of a sliding gate, as it pushes the brick from off the platform.

The portion 5 of the cam completes its circumference, and joins the termination of the part 4 with the beginning of part 1; this said portion 5 permitting of the descent of the plunger, by gravity or force suitably applied, to its normal or lowest position.

The cams $O O'$ are placed diametrically opposite each other, upon their shaft P ; consequently, when the roller of one flange, M , is resting upon the smallest diameter, 1, of its cam, the roller of the opposite plunger has mounted and stands upon the apex 4 of its cam.

The above comprises the mechanical construction and organization of a machine, as contemplated by my invention; its action being as follows:

Taking, as a starting-point, the position of the machine, as shown in the drawings, that is, with the roller of one plunger, or that plunger characterized by the letter M' , resting upon the smallest diameter 1 of its cam, and the roller of the opposite plunger M , upon the longest diameter 4 of its cam, and confining the description, for the present, to the half or side of the machine to the right of the drawings.

Clay, in its crude or raw state, or otherwise, is dumped into the tub or hopper A , in proper quantities, and the machine put in motion.

The clay, by the advance of the revolving wing c , is crowded into the inner or first portion a of one of the moulds, or that marked J , through the orifice d , in the bottom of the tub A , and, by the time the horizontal portion b , of the wing c , is over, and forms a cover to the orifice d , the longest point of the eccentric L , forces the horizontal plunger J inward, and drives the clay before it into the compression-chamber c of the mould J .

Upon the completion of this advance of the plunger J' , by the action of the eccentric, the portion 2, of the arm O' , impinges against the roller of the plunger M' , when the continued rotation of the cam, by the action of its tangential portion 2 upon the roller, elevates the plunger with great power, and compresses the brick within the mould to the desired extent; such brick, in the present instance, being reduced in thickness to that of the platform or bottom B of the tub, it being understood that the action of the wiper-cam V' , upon the rocker-shaft and lever l , has been such that the gate k' is now over the mouth of the mould, and serving as a top or cover to its compression-chamber.

Continuing its revolution, the cam does not further actuate the plunger M' until the portion 4 is reached, but in this interval the wiper V' has so actuated the lever l , and rocker-shaft m' , as to retract the gate k' from over the mouth of the mould, and leave an unobstructed passage for the compressed brick.

A continuation of the revolution of the cam through its part 4, elevates the plunger M' , within the mould, until the brick, which rests upon it, is brought above the platform B , when the wiper V' again actuates the rock-shaft and lever l , in such manner as to advance the gate k' and close the mouth of the mould, at the same time pushing the brick in advance of it from off the platform, and upon a revolving apron or belt, placed in a suitable position to receive it; the gate k' thus serving the purpose of a cover to the mould, and as a means of expelling the brick from the machine.

As the said gate completes its advance movement, and both expelled the brick and covered the mould, the cam O' has completed a revolution, which brings us to our starting-point, with the roller of the plunger M' resting upon the smallest diameter of its cam; it being observed that the eccentric L , after advancing the plunger J' , does not again actuate it until it has described a semi-revolution, and strikes the opposite plunger J , and begins to advance it.

As the two plungers are connected rigidly, the advance of the one marked J , of necessity, effects a retraction of that first mentioned, and marked J' .

Hence, while the cam O' is elevating the perpendicular plunger M' , within the compression-chamber of the mould I' , the eccentric L is retracting the horizontal plunger J' , and making room for the entrance of a new supply of clay to the inner portion of such mould.

As the eccentric retracts the first plunger J' , and begins to advance the second, J , the segmental flange or wings c , by the revolution of its drum, opens the orifice d' to the entrance of clay, and closes the orifice d in time to form a cover for the same against the advance of the plunger J .

As the mechanism upon opposite sides or halves of the machine is a duplicate of the other, in construction and operation, it is believed that the above explanation of the operation of the machine will be found sufficiently extended and lucid to enable a good mechanic to build it, it being apparent that when the perpendicular plunger upon one side of the machine is beginning its ascent, to compress the brick, its fellow-plunger has completed its ascent, and raised the brick to the surface of the platform B .

I would at this point call the reader's attention to the fact that the upper surface of the horizontal plungers J J' are scored longitudinally, in order to receive any excess of clay which would otherwise clog and retard the operation of the machine.

I would also call attention to the fact that the large diameter of the bottom of the revolving drum keeps the whole mass of clay in motion, and would state that I have contemplated, should practice determine necessary, to affix a series of pins about

the periphery of such drum, to the more effectively pulverize and agitate the clay within the hopper.

The reader will perceive that the operative mechanism of my machine is all disposed below the hopper A , thus avoiding the inconvenient and dangerous devices now generally situated over the heads of the laborers.

Although, from the proximity of the above description of the construction and operation of my invention, it is in reality very simple and compact, in comparison with others of its class, and may be produced at small comparative cost.

Its motions are all positive in their action, and, as will be apparent to the reader, the most laborious part of the work performed by the machine is borne by one cam.

Having thus explained the nature, operation, and advantages of my invention,

What I believe to be novel and original with myself, and desire to secure by Letters Patent of the United States, is as follows:

1. The combination, with the mould-box and its sliding cover and vertical plunger, operating in relation to each other as specified, of a plunger, arranged to move at right angles with the vertical plunger, and to feed the clay into the side of the mould, substantially as shown and described.

2. The employment, with the mould-box of a brick-machine, of two plungers or followers, operated substantially as described, the one to feed the clay into the side of the mould, and to exercise a lateral pressure upon the mass therein, the other to exert an upward or vertical pressure upon the clay, and to lift the formed brick from the mould, substantially as set forth.

3. The construction and arrangement of the vertical plunger, the peculiar-shaped cam, which imparts to the same its varied movements, and the devices for connecting said cam and plunger, substantially as shown and set forth.

4. The combination of the drum F , and the segmental flange which it carries, with the clay-hopper, and one or more feed-openings formed in that portion of its bottom intervening between the peripheries of the drum and the hopper, and arranged over corresponding feed-plungers, which carry to the moulds the clay delivered at regular intervals by the said segmental flange, substantially as shown and described.

5. The sliding cover for the mould, and oscillating lever for operating the same, in combination with the wiper, cam, and forked arm, which actuate said lever, to produce the reciprocating movement of the mould-cover, said parts being constructed and arranged substantially as shown and described.

6. The scoring or grooving the upper surfaces of the flanges J J' , to permit of return of surplus clay, when the same are employed in connection with the filling-wing c , the whole being as before explained.

7. As a machine for moulding and pressing bricks, the general arrangement and organization of individual features hereinbefore alluded to in detail, the same consisting mainly of the hopper A , with its orifices d d' , and provided with the drum F and segmental wing c , moulds I I' , provided with the dually-arranged plungers J M' , and gates or covers k k' , the said flanges being operated by the cams O O' , and the gate by the rocker-shaft m , forked arm p , and vibratory lever l , and the whole operating in manner and to produce results before set forth.

DAVID J. HUNTER.
